HANDBAG

Charles M. Lewis, New York, N. Y.

Application December 24, 1935, Serial No. 55,955

8 Claims. (Cl. 150—28)

This invention relates to portable receptacles and has particular reference to devices such as handbags of the knockdown type or employing removable or reversible covers.

- 5 One object of the invention is to provide a handbag including a wall structure adapted for embodiment in a one piece blank that can be opened up flat for laundering, and partition means so associated in an improved manner with the wall structure as to provide, in the assembled 10 relation therewith, a handbag from which articles however small cannot be lost, by reason of a closure coaction of the partition means with the wall structure.
- 15 Another object of the invention is to provide a handbag having openable end gusset means, and improved closure devices for the latter arranged to provide closed ended bag compartments and to prevent outward bulging of the limp gusset means.
- 20 Another object of the invention is to provide an improved handbag of the nature set forth having a partition or other wall or interconnection between the end gusset means, together with fastener means for closing the otherwise open 25 gussets and for engaging said interconnection with the gusset means.

Another object of the invention is the provision 30 of a handbag of the type mentioned having features of construction having different advantages singly and severally, including the following: the fastener means are not visible; the fastener means are uniform throughout and are easily operable; the partition and closure means are 35 wholly concealed in the bag; the partition means produces a uniform internal appearance of the bag; the partition means may serve as the sole reenforcing or stiffening part of the bag, which may otherwise be limp; the partition and closure 40 means producing a strain balancing effect in the gussets, permitting full capacity of the bag, supporting the body thereof with a minimum of bulkiness; the bag walls may be free of any fastening element for convenient laundering, although the device may include a reversible means 45 for closing the flap of the bag; and the different parts being adapted for a simple inexpensive construction and for convenient, durable and reliable use; as in a knockdown two part bag 50 structure.

Other objects and advantages of the invention will become apparent as the specification proceeds.

With the aforesaid objects in view, the invention consists in the novel combinations and ar-

rangements of parts hereinafter described in their preferred embodiments, pointed out in the subjoined claims, and illustrated in the annexed drawing, wherein like parts are designated by the same reference characters throughout the several views.

In the drawing:

Figure 1 is a perspective isometric view of a device with the flap open, and showing an embodiment of the invention. 10

Fig. 2 is a vertical sectional view thereof taken on line 2—2 of Fig. 1.

Fig. 3 is a horizontal sectional view on line 3—3 of Fig. 1.

Fig. 4 is an isometric perspective view of the 15 partition and closure means in detached condition.

Fig. 5 is a view in end elevation thereof.

Fig. 6 is a plan view in flat open condition of a blank providing the side wall and gusset structure of the bag. 20

Fig. 7 is a view of a fastening element in detached position, for holding the flap closed.

Fig. 8 is a fragmentary perspective view of a 25 modification of the invention.

The advantages of the invention as here outlined are best realized when all of its features and instrumentalities are combined in one and the same structure, but, useful devices may be produced embodying less than the whole. 30

It will be obvious to those skilled in the art to which the invention appertains, that the same may be incorporated in several different constructions. The accompanying drawing, therefore, is submitted merely as showing the preferred 35 exemplification of the invention.

Referring in detail to the drawing, 10 denotes a device such as a handbag embodying the invention. The same may include a blank 11 shown in Fig. 6 as consisting preferably of a one piece 40 member of a limp material. For reversibility, the blank may have different appearances or colors on its opposite faces, and hence may consist of two sheets of different materials secured together as along the edges thereof. 45

It is noted that the blank is generally rectangular and has an extension 12 adapted to provide a flap. The blank may be folded along longitudinal parallel lines 13, equally spaced inwardly of the side edges 14 of the blank. The flap may be foldable along the line 15, and the blank may be folded along one or more lines 16 which define the bottom fold of the bag. If desired, the fold lines 13 may be stiffened or hemmed, especially 50

55

if the blank 11 is not reversibly used, to thus produce sharp definition of the bag contour.

Extending along the side edges 14 are securing means of any suitable nature such as the 5 holes or perforations 17 which may have eyelets if desired.

It is noted that the sections 18 intermediate of the edges 14 and the fold lines 13 are relatively narrow to conserve material and are only of such 10 width as may be required for desired expansibility of the assembled gusset structure.

The blank may have a buttonhole 19 in the flap 12 thereof, and a buttonhole 20 in the lower part of the blank, the latter adapted for releasable 15 engagement with a device 21, which may comprise a pair of ordinary like buttons 22, directly interconnected as by a thread 23. On passing one button through the hole 20, the device 21 is mounted, with the other outside button available 20 for releasable engagement with the flap 12 at the buttonhole 19 thereof to thus close the handbag.

In addition to the blank 11, the only other essential part of the bag 10 is illustrated in principle in Fig. 4. The part 24 referred to may comprise closure means 25 for the openings in the gussets together with an interconnecting or spacing element 26, which may conveniently constitute a wall or central partition and thus secure 30 a strain balancing effect in the handbag. Since the member 24 is of relatively rigid character so as to constitute a shaping or body supporting means, by disposing the same centrally of the bag, a uniform gusset or accordion action is obtained 35 at the sides of the member 24, and the bag as a whole preserves a certain softness or pliability like that of the standard envelope bag, assuring the proper feel to the hand, and permitting a maximum capacity of bag volume in expansion.

40 Specifically, the member 24 may consist of two sheets of material 27 suitably secured together throughout except at their opposite end portions to thus provide wings 28 which are angularly movable apart from the apical lines 29. Due to 45 the stiffness of the wings 28, the same tend always to move toward each other to thus provide the clip-like holding or closure means.

Mounted on the wings 28 at the opposed faces of each pair thereof is a fastening means for a 50 supplemental securement of the gusset means if desired. For instance, as shown in Fig. 5, one of the wings may have studs 30 with suitably elongated shanks thereon, and the companion wing may have sockets 31 for resilient engagement 55 therewith. The studs are spaced to pass through corresponding holes 17 of a pair of gusset sections 18 at one end of the device 11, with the edge portions of the gusset sections housed between the wings 28 in a uniform and finished manner in the 60 assembled bag. The closure thus afforded may be characterized as a double lap joint.

If preferred, each sheet 27 may have its end portions infolded as shown at 32 in Fig. 3, the structure thus obtained having its parts interconnected as by a line of stitching 33. If the studs and sockets 30, 31 have been initially connected to the portions 32, it results that the parts 30, 31 are wholly concealed between the wings 28. Further a double thickness of the wings 28 is 70 thus obtained for increased strength and stiffness. It is noted that in the drawing, the showing of the fold portions 32 has been omitted in certain figures in order to obtain clarity.

The member 24 may be colored to correspond 75 to the color of one face of the blank 11 to thus

obtain added uniformity in the internal appearance of the bag. The said member may also have a mirror, pocket or the like provided therein or thereon in any well known manner, not shown herein.

To assemble the bag 10, the blank 11 is first folded along the lines 13 and then along the line 16. Thus a bag is provided, with open end gussets, since the sections 18 are free of each other. Now the member 24 is inserted with both 10 sections 18 received between a pair of wings 28 at each end of the bag, the studs being passed through corresponding holes 17 and snapped into engagement with the sockets 31. The bag is now 15 in assembled condition, and the device 21 may be attached, if desired, to complete the assembly. The bag thus obtained provides a plurality of longitudinal expansible pockets, separated by the partition 26 which may extend into close proximity to the bottom of the bag. The gusset means 20 may be of sufficient extent lengthwise of the bag to permit ample expansion without undue strain on the fastening means 25 to avoid accidental opening of the latter.

In Fig. 8 is shown a modification of the invention including a limp wall structure 11a having the edges of its gusset sections 18a provided with hems or bead portions 14a. The closure and partition means 24a may include a wall 26a having at each end a holding closure means 25a. 30 The latter may consist of a single sheet of metal, folded to provide a channel 35 adapted to be clamped on the wall 26a, and the flanges of the channel having reversely bent spaced walls 36 longitudinally lipped at 37 inwardly toward 35 each other. The channel member 25a may thus be secured with the gusset sections by a movement downward relative thereto, and with the beads 14a slidably removably received between the wings or flanges 36 of the channel section 40 and retained by the lips 37. The device may in other respects be like that shown at 10, and illustrative of a holding and closure means which does not require fasteners such as 30, 31, and which operates reliably by a clipping or clamping 45 action, or any securing means between the walls 36.

It will be appreciated that various changes and modifications may be made in the device as shown in the drawing, and that the same is submitted in an illustrative and not in a limiting sense, the scope of the invention being defined in the following claims.

I claim:

1. A portable receptacle including a one piece blank adapted to be opened up flat, said blank being longitudinally folded along lines spaced from the edges thereof, the portions between the fold lines and edges constituting gusset sections, said blank being transversely folded to provide side walls for the receptacle, a partition between said side walls, said partition having means secured thereto at opposite ends of the partition, each of said means providing a plurality of wings extending toward the adjacent gusset sections, the upright edge portions of the latter being received between said wings, said wings having means for releasable securement to said edge portions of the gusset sections to thus provide a continuous gusset structure at each end of the receptacle, said edge portions of the gusset sections being otherwise relatively free of each other and the said wings at each end of the receptacle cooperating with each other to 75

- constitute a closure that closely overlies said edge portions.
2. A handbag including a blank folded along longitudinal and transverse lines to provide side walls having upright marginal infolded gusset sections, and a removable separate single means comprising a partition wall and combined interconnecting and closure means at opposite ends of the partition wall and extending along the free upright edge portions of the gusset sections, said interconnecting and closure means including spaced wings for receiving said free edge portions of the gussets therebetween to provide a lap joint with the gusset sections, the interconnecting and closure means cooperating with said edge portions of the gusset sections to tend to prevent separation of the edge portions.
3. A handbag including a bag having side walls provided with infolded upright marginal gusset sections, the latter having their upright edge portions at each end of the bag separable from each other, a partition means between the side walls, said partition means providing spaced companion end portions extending along the gusset sections at each end of the bag and receiving said edge portions therebetween, and releasably fastening means between the companion end portions, including a male element on one end portion, a female element therefor on the other end portion, and the gusset sections having holes adapted to receive the male element so that upon interengaging said elements the gusset sections are interconnected to provide closed gussets with the latter interengaged between the ends of the bag by the partition means, the latter being otherwise relatively free of the bag, and the bag being thus free of fastening means which will prevent reversibility and laundering thereof upon removal of the partition means.
4. A handbag including a bag consisting of a blank folded longitudinally and transversely to provide side walls and upright marginal infolded end gusset sections, partition means between the side walls, said partition means comprising interconnected spaced end portions receiving therebetween the upright free edge portions of the gusset sections, fastening means between the spaced end portions, said fastening means including male elements, and the gusset sections having holes for releasable reversible engagement with the male elements, and the spaced end portions thus having lapped closure relation with the gusset sections in the assembled condition of the handbag, the said blank, in the disassembled condition of the handbag, being adapted to be opened flat and being thus free of projecting fastener parts.
5. A handbag including a bag consisting of a blank foldable along longitudinal and transverse lines to provide side walls having upright infolded marginal gusset sections at each end of the bag, partition means between the side walls, the partition means including a plurality of relatively stiff sheets of material disposed face to face, the sheets of material having at their opposite ends infolded upright wing portions secured together in spaced relation to the fold lines of the wing portions, fastener means between the wing portions, including fastener elements connected solely to the inner fold sections of the wing portions, the gusset sections having free upright edge portions received between the wing portions at each end of the bag and being releasably engaged by the fastener means.
6. A handbag including a bag having side walls, the latter having infolded marginal upright gusset sections, a partition between said walls, said partition having interconnected upright wing portions at each end thereof, the gusset sections having free upright edge portions received between said wings, and fastening means located wholly between the wings for releasably interconnecting said free edge portions with each other and with the wings to thus provide closed gussets.
7. A handbag including a bag having side walls, infolded marginal upright gusset sections therefor, a wall intermediate of the side walls, means connected to the intermediate wall at the ends thereof, said means each providing a channel member having marginal inturned lips along the flanges thereof, the gusset sections having free edge portions provided with upright bead like elements receivable in the channel member and releasably retained by engagement of said lips with said elements.
8. A handbag including a bag having side walls, the latter having upright inturned marginal gusset sections at the ends of the bag, said gusset sections having upright free edge portions in relative proximity to the ends of the bag, means at each end of the bag for releasably interconnecting said free edge portions, and means extending longitudinally of the bag for interconnecting the first mentioned means, the first and second mentioned means constituting a removable unit.

CHARLES M. LEWIS. 55
